HAT BLOCKING MACHINE

Lemey G. Blount, Little Rock, Ark.

Application June 4, 1938, Serial No. 211,877

24 Claims. (Cl. 223—12)

The present invention relates to a hat blocking machine and refers particularly to a machine adapted for use in pressing establishments for steaming and pressing hats.

5 An object of the invention is the provision of a machine capable of easily and quickly pressing a hat brim without injuring the interior of the hat or burning the sweat band during the pressing operation.

10 Another object is to provide a machine capable of rapid adjustment to accommodate hats within a wide range of sizes.

Another object is the provision of a machine capable of producing a sharp crease at the point 15 where the brim joins the crown of the hat and at the same time completely sealing the sweat band from injury by the heating medium during the creasing and pressing operation.

Another object is to provide a sweat band protector which is adjustable to accommodate hats 20 of various sizes. This protector comprises a flexible, covered spring steel band capable of being coiled upon itself to a size where it can be placed in a hat then uncoiled without restraint into clamping engagement with the sweat band.

25 A further object is to provide a hat receiving receptacle having a steam heating coil surrounding a brim pressing mechanism, in combination with a hat steaming kettle connected to one end of the steam coil whereby steam, after passing through the coil, will enter the kettle and effect a preliminary steaming operation on the exterior 30 of the hat prior to its introduction into the brim pressing receptacle.

35 With the foregoing and other objects in view, the invention will now be more particularly described, reference being had to the accompanying drawings, wherein:

Figure 1 is an enlarged vertical section through 40 the hat brim pressing receptacle and its supporting frame;

Figure 2 is a front elevation of the machine;

Figure 3 is a side elevation thereof;

Figure 4 is a plan view partly in section of the 45 machine;

Figure 5 is a detail of the mechanism for actuating the curved sheet clamping arms;

Figure 6 is a view of the sweat band protecting band, and

50 Figure 7 is a section on line 7—7 of Figure 6.

Referring to the drawings, the machine comprises generally a supporting frame or table upon which is mounted a receptacle or chamber open at its top. This receptacle may be either cylindrical or elliptical in cross section, and is pro-

vided with a steam heating coil positioned adjacent its side walls. A sheet or bag of canvas or other suitable fabric extends transversely of the receptacle and is secured thereto adjacent its open upper end. This sheet covers the steam 5 coil and also a steam outlet located in the bottom of the receptacle. Means are provided which cooperate with the canvas sheet to clamp a hat in upright position in the receptacle upon the sheet while steam is introduced below the hat, 10 to effect a quick and efficient pressing of the hat brim and produce a sharp crease where the brim turns up from the crown. Before the steam is introduced into the bottom of the receptacle, it is first passed through the coil to initially heat the 15 receptacle. In this connection the steam from the coil is utilized to give the exterior of the hat a preliminary steaming. This is accomplished by connecting the end of the coil to a double walled 20 kettle or container positioned exteriorly of the receptacle and preferably mounted on the supporting frame. Thus, the steam first passes through the coil, and then enters the kettle to give the hat a preliminary steaming while the hat is on a block. Thereafter the hat is removed 25 from the kettle and lured in the usual manner. It is then placed in inverted position in a flange stand and flange of appropriate size and shape. The hat is then clamped in the flange stand by a 30 specially constructed flexible metal band covered with canvas or other suitable material. This band is capable of being coiled upon itself to a size which will permit it to be placed in the hat. The band is then released and allowed to uncoil about and completely cover the sweat band of the 35 hat, thereby functioning as a means for detachably clamping the hat in the flange stand and for completely sealing and protecting the sweat band from live steam when it is subsequently introduced into the bottom of the receptacle. With 40 the metal covered band in position within the hat, the flange stand and hat are placed in upright position in the receptacle in contact with the flexible sheet or canvas bag. Means are then operated to securely clamp the stand and 45 hat in the receptacle so that the flexible sheet will have a pressing effect upon the hat brim. Steam is then introduced into the bottom of the receptacle where it acts on the sheet pressed brim. 50 The hat is maintained in clamped position until the steam has had the desired effect of pressing and creasing the hat, whereupon the hat may be released and removed from the receptacle. If desired, means are provided to evacuate the un- 55

condensed steam from the receptacle before the hat is removed.

Referring now to Figures 1 to 3, the numeral 10 designates a supporting frame or table having uprights or legs 11 which suitably support a table top 12. Both the frame 10 and top 12 may be formed of wood, metal, or any other suitable material, as desired. A substantially cylindrical receptacle 13 of drum-like formation is mounted on the top 12 and is provided with vertical side walls 14 terminating in an open top. The bottom or base 15 of the receptacle 13 rests upon the top 12 and is provided with a central depending portion 16 projecting through an opening in the table and resting upon a plate 17 forming a part of the supporting frame 10.

A flexible sheet or bag 18 of canvas or other fabric is located adjacent the upper open end of the receptacle and completely envelops the same; 20 that is, the sheet extends transversely of the receptacle and is adapted to materially assist in the brim pressing operation, as will be presently described. While the sheet 18 may be secured directly to the rolled top 19 of the receptacle, I 25 prefer to secure the edges of the sheet so that it may be adjusted to different positions with respect to the interior of the receptacle. For this reason, the peripheral portions of the sheet are preferably riveted between inner and outer metal 30 hoops or bands 20 and 21, respectively. As shown in Figure 1, these hoops surround the receptacle and are slightly spaced from the same. In order to adjust the bands and sheet 18, there are provided a plurality of spaced posts 22 secured to 35 the table 12 exteriorly of the receptacle 13. Each post is provided with a slot 23, see Figures 2 and 3, through which projects the shank of a bolt 24. Each bolt is secured to the outer ring 21 and is 40 threadedly associated with a wing nut 25 which cooperates with the bolt to clamp the bands and sheet in different positions of adjustment upon the posts 22.

Referring again to Figure 1, a hat supporting pad 26 is mounted centrally of the receptacle by 45 means of a hollow post 27. This post passes through the depressed portion 16 of the receptacle and is secured to the plate 17 of the supporting frame 10. The pad 26 comprises a flexible rubber or other fluid impervious and heat insulating material 28, which is preferably of oval 50 contour and is of an area to accommodate hats of various sizes. A metal base 29 directly supports the rubber pad 28, and this is directly connected to the top of the post 27. For a purpose 55 to be hereinafter described, I also provide a sheet engaging button 30 which is connected to the top end of a post 31 passing through the center of the pad 26 and slideable in the post 27. The lower end of the post 31 is provided with an enlargement 32, and this, together with the post and button 30, is normally urged into upward position 60 by means of a coil spring 33 positioned in the hollow post 27 below the enlargement 32.

At one side of the table top 12 is mounted a 65 rod 34, the upper end of which terminates a substantial distance above the open top of the receptacle 13. A clamp supporting arm 35 is 70 rotatably mounted upon the upper end of rod 34, and carries at its free end a clamping member 36. The upper end of this member is threaded and passes through a threaded collar 37 pivotally secured between a yoke 35'. This yoke is 75 provided with a threaded shank 36' engageable with a threaded opening in the free end of the arm 35. This arrangement permits the yoke and

member 36 to swing relative to the arm 35. At the same time the member 36 is capable of swinging movement on the yoke 35'. The threaded connection between the member 36 and collar 37 is merely to permit the member to be adjusted to 5 accommodate different size flange stands. Otherwise the member 36 and collar 37 are adapted to be locked against relative movement. The purpose of the member 36 is to detachably clamp a 10 hat in brim pressing position upon the top of the flexible sheet 18. It is essential that the member 36 and arm 35 be locked in operative position, and I, therefore, provide a latch 38 extending longitudinally of the arm 35 and slidably supported thereby in elements 39 and 40 of the arm. 15 The element 40 is of sufficient size to house a coil spring 41 which normally urges the latch element 38 into the position shown in Figure 1. The enclosed end of the latch passes through an opening 41' in the hub 42 of the arm 35, and this opening 20 is adapted to register with one of a plurality of spaced openings 43 formed in the upper end of the rod 34 and enclosed by the hub 42.

When it is desired to move the clamping member 36 to different positions of adjustment, it is 25 necessary merely to pull out on the handle 44 against the tension of the spring 41 and release the inner end of the latch 38 from one of the holes 43. The clamping member and arm 35 may be moved about the rod 34 to the desired 30 position of adjustment. When the handle is released, the spring will urge the end of the latch into engagement with one of the holes 43 with which the latch and hole 41' are in register, and thereby lock the clamping member against movement relative to the rod 34.

Referring to Figures 6 and 7, there is disclosed a flexible clamping band 45 which is adapted to clamp a hat in a flange stand prior to the brim pressing operation and to protect the sweat band 40 from injury. This band comprises one or more flexible steel strips 46 which is completely enclosed by a canvas or other fabric covering 47. As shown, the covering provides a pocket within which the metal band is inserted, and the width 45 of the covering is substantially greater than the width of the spring, for the purpose of shielding a substantial portion of the interior of a hat when the band is placed therein. The steel strip 46 is sufficiently flexible to permit the band to 50 be coiled upon itself so that it may be readily placed in position to clamp a hat to a flange stand.

With the construction as thus far described, and assuming that it is desired to press the hat 55 brim subsequent to steaming the exterior of the hat, a hat 48 is placed in inverted position in a flange stand 49, upon which a flange 50 of the desired size and shape has been mounted. The operator then coils the flexible steel band 45 upon 60 itself and inserts it in the hat where it automatically expands to a position in which it will not only tightly clamp the hat to the flange stand, but will also completely cover the sweat band of the hat and a considerable portion of the interior 65 of the hat above the sweat band. The flexible sheet or bag 18 will, of course, completely cover the upper portion of the receptacle 13 and will 70 overlie the pad 26 and button 30. The flange stand with the hat clamped therein is then placed within the receptacle upon the flexible sheet with the hat in upright position. This flange stand may be positioned in the receptacle by hand, but I prefer to use the mechanism shown in the drawings, wherein the flange stand 49 is connected to a 75

hinged element 51 mounted at one side of the front of the table 12. This element comprises a sectional hinged strap having a section 52 secured directly to the table. A substantially U-shaped section 53 is hinged to the section 52, and has its free end secured to the base of the flange stand 49, see Figures 1 and 4. With this construction, a hat, after being clamped in the stand, may, together with the stand, be easily 10 and quickly swung upwardly and into correct pressing position in the receptacle. The element 51 is so associated with the receptacle that the flange stand and hat will contact the flexible sheet 18 and come to rest directly over the pad 15 26 and button 39 as clearly shown in Figure 1. If desired, another element 51 may be mounted on the other side of the table so that one hat may be clamped in a flange stand, while the other hat is in the receptacle being pressed.

20 The clamping member 36 is then swung about the rod 34 until the member is over the flange stand. In moving the member 36 to clamping position it is initially swung, with the yoke 35, out of a true vertical position. That is, the member and yoke are rotated slightly on the arm 35. In this position the knob 54 on the lower end of the member 36, is placed on the recess 55 in the top of the flange stand 49. Then the member is moved to a vertical position. This will produce 25 a downward thrust of the member 36 on the flange stand and clamp the flange stand and hat in the receptacle. The handle 44 may then be released, whereupon the latch 38 will lock the member 36 and arm 35 against rotary movement 30 with respect to the rod 34.

40 Referring to Figure 1, it will be observed that the button 39 will project upwardly within the interior of the hat and thereby stretch the flexible sheet or bag 18 to some extent up within the crown of the hat. However, while the flange stand and hat are securely clamped upon the pad 26 in the receptacle 13, it is necessary that additional means be provided to effectively pull the sheet 18 taut around the hat brim into brim 45 pressing position. In the present instance, I have provided means which efficiently press and hold the flexible sheet in operation while the brim pressing operation is being performed. This means, see Figures 1 and 4, comprises a plurality of curved arms 56 which are pivotally mounted to swing to and from the flange stand and hat to accommodate hats of various sizes.

50 Four of these curved arms are provided, and each is detachably mounted on a shaft 57 located adjacent the side wall 14 of the receptacle. As shown in Figure 4, the arms 56 are preferably arranged in pairs, with the arms of each pair crossing one another and being spaced from the arms of the other pair when in inoperative position. Furthermore, the pairs of arms are so positioned 55 that they will be at opposite ends of the hat as distinguished from opposite sides of the hat when the hat is placed in the receptacle. In moving the arms to and from the center of the receptacle, it will be observed that the shafts 57 of each pair will rotate in opposite directions; that is, one shaft will rotate in a clockwise direction while the other shaft will rotate in a counter-clockwise direction. The shafts 57 pass through 60 the bottom 15 of the receptacle and are pivotally mounted in the supporting frame 11 so that they may be rotated in unison to move the arms inwardly and outwardly with respect to the flange stand and hat.

65 70 The means for effecting this unitary pivotal

movement of the shafts 57 is as follows: The shafts 57 pass through openings in a spider or saddle 58 which is supported between a pair of spaced cross bars 59 connecting the legs 11 and forming a part of the frame 10. Each shaft is rigidly connected to one of four levers 60, 61, 62, 63, the hubs of which rest upon the saddle. As will be observed, the inner ends of the levers 60, 61 overlap and are provided with a slot and pin connection 64 whereby movement of one lever 10 about its pivot will impart movement to the other lever. Likewise, the inner ends of levers 62 and 63 overlap and are connected by a slot and pin connection 65.

In order that the levers and shafts may be rotated in unison, the levers 60 and 62 are pivoted to cross links 66 and 67 respectively, see Figure 5. The inner ends of these links are pivoted, each to one end of a central lever 68 which is centrally pivoted at 69 to the saddle 58. An operating lever 70 is rigidly secured to the lever 68 at its pivot point and has its free end projecting beyond the confines of the saddle. In order that it may be conveniently grasped by the operator and moved about the pivot 69 when it is desired to rotate 25 the shafts 57 and arms 56, the outer end is extended toward the front of the table, see Figure 5. Movement of the operating lever 70 will rotate the center lever 68 about its pivot, thereby actuating the links 66 and 67 which will, in turn, 30 operate the levers 60, 61, 62, 63 in unison. This action will rotate the shafts 57 simultaneously and move the arms 56 inwardly or outwardly with respect to the flange stand 49 and hat 48. In order to lock the operating lever 70 in different 35 portions of adjustment there is provided a curved bar 71 carried by the saddle 58 and having its upper edge formed with ratchet teeth 72, which engage and hold the operating lever in each position of adjustment. If desired, the forwardly extending portion of the handle 70 may be supported on the frame 10 whereby downward pressure on the extreme front end of the handle will lift the handle clear of the ratchet teeth 72.

40 Normally, the arms 56 are located upon the bottom 15 of the receptacle 12. However, to secure the desired pressing effect of the flexible sheet 18, it is necessary that arms 56 and their shafts 57 be raised into clamping engagement with the sheet 18, as well as being moved about their pivots. The unitary raising and lowering of the arms 56 and the shafts 57 is accomplished in the following manner. Normally the saddle 58 rests upon the pair of spaced bars 59 which form part of the supporting frame and extend longitudinally thereof between the uprights 11. These bars, similar to the saddle 58, are provided with openings through which the shafts 57 project and which permit vertical sliding movement of the shafts during the arm raising operation.

45 50 55 60 65 70 75 A substantially U-shaped rod 73 has the upper end of its legs connected to the saddle 58 at a point substantially centrally thereof. The base portion 74 of the rod 73 is positioned a substantial distance below the saddle 58 and is pivotally connected to the inner end of a foot operated lever 75. This lever is pivoted on a cross bar 76 extending between the uprights 11 and forming a part of the supporting frame 10. The outer end of the lever 75 is provided with a foot engaging plate 77. A latch 78 is pivoted to the base of the frame 10 and is provided with a plurality of ratchet teeth 79, which engage the lever 75 and lock the same in different positions of adjustment. The lower end of the latch 78 is provided 75

with a foot flange 80, and a coil spring 81 is positioned between this flange and the lower portion of the frame 10 to normally urge the catch into locking engagement with the lever 71.

Assuming that the curved arms 56 are resting upon the bottom of the receptacle and it is desired to raise the same into contact with the flexible sheet 18, it is merely necessary to apply foot pressure to the plate 71. This will move the lever 75 about its pivot and raise the U-shaped rod 73, and saddle 58. Since the levers 60, 61, 62, 63 are supported on the saddle, these will also be raised, and consequently raise the shafts 57 and curved arms 56 in unison.

When it is desired to move the flexible sheet 18 into pressing engagement with the brim 82 of the hat, after the flange stand and hat have been clamped in the receptacle, as above described, the arms 56 may first be moved about 20 their pivots to adjust them to the correct size for the hat being pressed, by actuating the operating lever 70. This will bring the arms into contact with the sheet 18. Thereafter, the arms may be raised upwardly about the sheet to the 25 position shown in Figure 1 by actuating the lever 75. If desired, this procedure may be reversed; that is, the shafts and arms may first be raised, and the arms then rotated inwardly to press the sheet 18 about the hat and flange stand. However, regardless of the procedure, the sheet 18 will be drawn tightly about the hat brim and maintained in this position as long as necessary. It is possible that sufficient pressure will be exerted on the sheet 18 by the arms 56 to move the 30 button 30 and post 31 downwardly against the tension of the spring 33. However, this will have no material effect upon the pressing operation of the sheet, since the latter will merely be shifted slightly with respect to the hat brim. In any 35 event, the sheet 18 will project upwardly into the crown of the hat and will be drawn tightly about the brim 82, pressing the same against the flange 50, so that a sharp crease will be produced at the point where the brim joins the crown of the hat. With the hat clamped to the sheet in 40 this manner, steam is introduced into the bottom of the receptacle, as well as around the side walls of the same.

Referring to Figures 1, 2, and 4, there is disclosed a system of piping for heating the receptacle 13, and for admitting live steam to the interior of the receptacle. The numeral 83 indicates a steam line leading from any suitable source of steam supply, not shown. This line leads directly to a steam coil 84, see Figures 1 and 4, which is positioned adjacent the vertical side wall of the receptacle, and also extends across a portion of the bottom 15. Steam passing through this coil is designated to preliminarily heat the receptacle prior to the brim pressing operation. The steam enters at the top of the coil 84 and after circulating within the receptacle, leaves through a line 85 which connects with a steam kettle 86 whereby the steam for heating the receptacle is also utilized for heating the kettle 86. This kettle will be described in detail hereinafter.

Referring again to Figure 2, it will be observed that the steam line 83 is provided with a branch 70 87 leading to a point beneath the table 12. The pipe 87 terminates in an upwardly extending section 88 projecting through the bottom 15 of the receptacle 13. In order that the steam, as it enters the receptacle, will be distributed about 75 that portion of the flexible sheet 18 which is

clamping the hat brim 82 to the flange 50, a baffle 89 is employed, having a hub 90 which is secured to and embraces the post 27. The branch line 87 is provided with a valve 91, see Figure 2, for closing off this line until it is desired to admit steam into the bottom of the receptacle. Assuming, therefore, that the valve 91 is closed, steam will initially pass through the coil 84 and preliminarily heat the receptacle prior to clamping the hat and flange stand in operative position. After 10 the hat has been clamped in the receptacle, as shown in Figure 1, the valve 91 is then opened to permit steam to pass through the branch line 87 and discharge into the bottom of the receptacle. The baffle 89 will evenly distribute the steam so 15 that it will readily come into contact with the portion of the flexible sheet 18 which is pressing the brim 82 to the flange 50. Since the hat is clamped to the pad 26, steam is prevented from entering the interior of the hat. Furthermore, 20 the sweat band and other interior portions of the crown of the hat are additionally protected from injury by the live steam, because of the clamping band 45.

The steam is introduced through the pipe section 88 as long as desired and until it is considered that the brim has been effectively pressed. Thereafter, the valve 91 is closed, and the hat and flange removed from the receptacle after first releasing the arms 56 and the clamping member 36. If it is desired to remove the steam from the receptacle and cool the hat prior to its removal, means are provided to draw off the steam from the receptacle.

As will be observed, the post 27 and hub 90 are provided with aligned openings 92 which communicate with a central opening 93 leading to a discharge pipe 94. This pipe, exteriorly of the frame 10, is connected with the line 85 leading from the coil 84, and is adapted to be shut off therefrom by means of a valve 95. Assuming that the valve 96 leading to the kettle 86 is closed and the valve 95 is opened, steam will pass through the valve 95 and the discharge pipe 94. This will produce a suction or evacuating action 45 upon the discharge pipe 94 whereby the steam remaining in the receptacle will be drawn through pipe 94 and discharged through the pipe 97. Of course, any condensation will readily pass from the lower end of the receptacle through 50 the passage 93 and discharge pipe 94.

Referring again to Figures 2 and 4, it will be observed that the kettle 86 is of double-wall formation consisting of the inner wall 98 and the outer wall 99. The steam passing through the pipe 85 from the lower end of the coil 84 will enter the top of the kettle and flow between the walls 98 and 99. Assuming that a hat is placed in the kettle to be steamed preliminary to the brim pressing operation, it will be initially heated by indirect contact through the wall 98 and will then be acted upon by direct contact with the steam. Furthermore the steam will quickly heat the inner wall 98, and thereby prevent it from sweating and wetting the hat before it is acted on by direct contact with the steam. This steam will first pass down to the bottom of the kettle and then rise through the centrally disposed opening 100 in contact with the outside of the crown of the hat. A discharge pipe 101 is connected to the lower end of the outer wall 99 to permit any condensation to easily drain from the kettle. An air escape opening 102 is provided adjacent the top of the kettle at a point opposite to the steam inlet to permit air to 75

escape as the steam is introduced into the kettle. Otherwise, air would be trapped in the top of the kettle and interfere with the steaming operation. With the present construction, as above described, it will be apparent that the crown of a hat may be easily and quickly steamed prior to its introduction into the brim pressing receptacle, by the steam which is utilized to heat the walls of the receptacle. It is, of course, to be understood that the crown is to be lured in the usual manner prior to the brim pressing operation.

It is to be further understood that various changes may be made without departing from the spirit of the present invention. For instance, it is possible that the brim pressing operation may be performed without the use of the pad 26, since the flexible band 45 will sufficiently protect the sweat band and interior of the hat from the steam. Therefore, it is merely necessary that some means be provided to support the hat in raised position relative to the bottom of the receptacle. Of course, the pad 26 constitutes a good support and doubly insures the sweat band from being burned or otherwise injured by the steam.

I claim:

1. In a hat brim pressing machine, a receptacle open at its upper end, a flexible sheet forming a pressing element extending transversely of said receptacle, means for clamping a hat in upright position on said sheet whereby the sheet will be drawn into pressing engagement with the brim of the hat, and means for applying steam in the vicinity of the hat brim while the latter is pressed to the flexible sheet.

2. In a hat brim pressing machine, a receptacle open at its upper end, a flexible sheet forming a pressing element extending transversely of said receptacle, means for clamping a hat in upright position on said sheet whereby the sheet will be drawn into pressing engagement with the brim of the hat, and means for introducing steam into the receptacle below the flexible sheet while the latter is clamped to the hat.

3. In a hat brim pressing machine, a receptacle open at its upper end, a flexible sheet forming a pressing element extending transversely of said receptacle, means for clamping a hat in upright position on said sheet whereby the sheet will be drawn into pressing engagement with the brim of the hat, a steam heating coil mounted within the receptacle beneath the flexible sheet and adapted to transmit heat to the hat during the pressing operation, and a steam pipe opening into the receptacle below the sheet to permit steam to be introduced into the vicinity of the hat brim while the latter is clamped to the flexible sheet.

4. In a hat brim pressing machine, a receptacle open at its upper end, a flexible sheet forming a pressing element extending transversely of said receptacle, means for clamping a hat in upright position on said sheet whereby the sheet will be drawn into pressing engagement with the brim of the hat, means for introducing steam into the receptacle below the flexible sheet while the latter is clamped to the hat, and means for sealing the interior of the hat against the introduction of steam during the brim pressing operation.

5. In a hat brim pressing machine, a receptacle open at its upper end, a flexible sheet forming a pressing element extending transversely of said receptacle, means for clamping a hat in

upright position on said sheet whereby the sheet will be drawn into pressing engagement with the brim of the hat, means for introducing steam into the receptacle below the flexible sheet while the latter is clamped to the hat, and means for sealing the interior of the hat against the introduction of steam during the brim pressing operation, said means including a fluid impervious pad supported within the receptacle and engageable with the portion of the flexible sheet contacting the brim.

6. In a hat brim pressing machine, a receptacle open at its upper end, a flexible sheet forming a pressing element extending transversely of said receptacle, a clamping member located above the flexible sheet and adapted to press a hat into engagement therewith, means positioned within the receptacle beneath the sheet and adapted to be moved into contact therewith to draw the latter into pressing engagement with the hat brim, and means for applying heat in the vicinity of the hat brim while the latter is pressed to the flexible sheet.

7. In a hat brim pressing machine, a receptacle open at its upper end, a flexible sheet forming a pressing element extending transversely of said receptacle, a clamping member located above the flexible sheet and adapted to press a hat into engagement therewith, a plurality of arms pivotally supported by the receptacle and adapted to be moved into contact with the flexible sheet to draw the latter into pressing engagement with the hat brim, and means for applying heat in the vicinity of the hat brim while the latter is pressed to the flexible sheet.

8. In a hat brim pressing machine, a receptacle open at its upper end, a flexible sheet forming a pressing element extending transversely of said receptacle, a clamping member located above the flexible sheet and adapted to press a hat into engagement therewith, a plurality of curved arms pivotally mounted in the receptacle below the flexible sheet and adapted to be moved into contact with said sheet to draw the latter into pressing engagement with the hat brim, and means for applying heat in the vicinity of the hat brim while the latter is pressed to the sheet.

9. In a hat brim pressing machine, a receptacle open at its upper end, a flexible sheet forming a pressing element extending transversely of said receptacle, a clamping member located above the flexible sheet and adapted to press a hat into engagement therewith, a plurality of curved arms pivotally mounted in the receptacle below the flexible sheet, means for moving the arms about their pivots to adjust them to different size hats, means for raising the arms to draw the flexible sheet into pressing engagement with the hat brim, and means for applying heat in the vicinity of the hat brim while the latter is pressed to the sheet.

10. In a hat brim pressing machine, a receptacle open at its upper end, a flexible sheet forming a pressing element extending transversely of said receptacle, means for clamping a hat in upright position on said sheet, whereby the sheet will be drawn into pressing engagement with the brim of the hat, a flexible fluid impervious pad supported within the receptacle beneath the flexible sheet and adapted to contact the sheet where the latter engages the inner portion of the hat brim, to seal the interior of the hat against the introduction of steam, and a resiliently mounted post extending upwardly through the pad and engageable with the flexible sheet within the confines

of the hat to facilitate the pressing action of the sheet.

11. In a hat brim pressing machine, a receptacle open at its upper end, a flexible sheet forming a pressing element extending transversely of said receptacle, a hat support including a flange stand, a flexible covered metal strip adapted to be coiled and positioned within a hat to removably clamp the hat in the stand and 10 protect the sweat band of the hat against the action of steam, means for clamping the hat and stand in upright position on said sheet whereby the sheet will be drawn into pressing engagement with the brim of the hat, and means for introducing steam into the receptacle below the flexible sheet while the latter is clamped to the hat.
12. In a hat steaming and pressing machine, a hollow receptacle, a steam heating coil positioned adjacent the side walls of the receptacle, 20 means for supporting and clamping a hat within the coil in position to press the brim of the hat, means for introducing steam into the receptacle for use in the brim pressing operation, and a hat steaming kettle positioned exteriorly of the receptacle and connected to the lower end of the heating coil whereby the steam after passing through the coil will enter the kettle and effect a steaming operation on the hat prior to the brim pressing operation.
13. In a hat brim pressing machine, a receptacle open at its upper end, a flexible sheet forming a pressing element extending transversely of said receptacle, means for clamping a hat in upright position on said sheet whereby the sheet 30 will be drawn into pressing engagement with the brim of the hat, means for introducing steam into the receptacle below the flexible sheet while the latter is clamped to the hat, means for sealing the interior of the hat against the introduction of steam during the brim pressing operation, and a drain pipe connected to the bottom of the receptacle for permitting the steam and condensation to discharge from the receptacle.
14. In a hat brim pressing machine, a receptacle open at its upper end, a flexible sheet forming a pressing element extending transversely of said receptacle, a clamping member located above the flexible sheet and adapted to press a hat into engagement therewith, and means positioned within the receptacle beneath the sheet 40 and adapted to be moved into contact therewith to draw the latter into pressing engagement with the hat brim, said means permitting relative movement between said sheet and means to provide uniform pressure upon all portions of the hat brim.
15. In a hat brim pressing machine, a receptacle open at its upper end, a flexible sheet forming a pressing element extending transversely of said receptacle, a clamping member located above 50 the flexible sheet and adapted to press a hat into engagement therewith, and a resiliently mounted post positioned within the receptacle beneath the sheet and adapted to cooperate with the clamping member to draw the sheet into pressing engagement with the hat brim, said post being unattached to said sheet and capable of movement relative thereto to permit uniform pressure upon all portions of the hat brim.
16. In a hat brim pressing machine, a receptacle open at its upper end, a flexible sheet forming a pressing element extending transversely of said receptacle, a clamping member located above 60 the flexible sheet and adapted to press a hat into engagement therewith, and a plurality of curved 70 arms pivotally mounted in the receptacle below the flexible sheet and adapted to be moved into contact with said sheet to draw the latter into pressing engagement with the hat brim.

17. In a hat brim pressing machine, a receptacle opened at its upper end, a flexible sheet forming a pressing element extending transversely of said receptacle, a clamping member located above the flexible sheet and adapted to press a hat into engagement therewith, a shaft 10 supporting saddle mounted below the receptacle, a plurality of shafts pivotally mounted in said saddle and projecting upwardly into the receptacle below the flexible sheet, sheet engaging arms carried by the upper ends of the shafts, and 15 means for operating said saddle and shafts to move the arms into contact with the flexible sheet and thereby draw the latter into pressing engagement with the hat brim.

18. In a hat brim pressing machine, a receptacle opened at its upper end, a flexible sheet forming a pressing element extending transversely of said receptacle, a clamping member located above the flexible sheet and adapted to press a hat into engagement therewith, a shaft 20 supporting saddle mounted below the receptacle, a plurality of shafts pivotally mounted in said saddle and projecting upwardly into the receptacle below the flexible sheet, sheet engaging arms carried by the upper ends of the shafts, means 30 for raising and lowering the saddle, and means for rotating the shafts about their pivots to move the arms into contact with the sheet to draw the latter into pressing engagement with the hat brim.

19. In a hat brim pressing machine, a receptacle open at its upper end, a flexible sheet forming a pressing element extending transversely of said receptacle, means for clamping a hat in upright position on said sheet whereby the sheet will be drawn into pressing engagement with the brim of the hat, a baffle mounted in the receptacle below the flexible sheet and adapted to direct steam into the vicinity of the hat brim, and means for introducing steam into the receptacle 40 below the baffle.

20. In a hat brim pressing machine, a receptacle open at its upper end, a flexible sheet forming a pressing element extending transversely of said receptacle and having its marginal portions projecting exteriorly of said receptacle, a band secured to the marginal portions of said sheet exteriorly of the receptacle, a plurality of posts positioned about the receptacle, means for adjustably clamping said band to said posts to adjust the sheet relative to the receptacle, and means for clamping a hat to said sheet whereby the sheet will be drawn into pressing engagement with the hat.

21. In a hat brim pressing machine, a receptacle open at its upper end, a flexible sheet forming a pressing element extending transversely of said receptacle, and means for clamping a hat and flange stand into pressing engagement with said flexible sheet, said means including an upright post supported on said machine and extending above the flexible sheet, an element carried by the upper post and movable toward and away from a position over the sheet, and a clamping member movably carried by said element and adapted to be swung to an upright position into clamping engagement with the flange stand.

22. In a hat brim pressing machine, a receptacle open at its upper end, a flexible sheet form-

ing a pressing element extending transversely of said receptacle, and means for clamping a hat and flange stand into pressing engagement with said flexible sheet, said means including an upright post supported on said machine and extending above the flexible sheet, a horizontal bar pivotally mounted at the upper end of said post and movable toward and away from a position over the sheet, and a clamping member pivotally mounted on the free end of said horizontal bar and adapted to be swung to an upright position whereby its lower end will engage the flange stand and exert downward pressure on the stand to press the stand and hat against the flexible sheet.

23. A device for steaming hat crowns comprising a double walled bowl shaped hat receiving kettle, the inner wall of which is adapted to receive and directly support a hat and which is imperforate except for a centrally disposed opening in its base, the outer wall having a steam inlet adjacent its top and an air outlet positioned

on the opposite side of the kettle from the steam inlet, and a valve positioned exteriorly of said kettle for controlling the flow of steam through said steam inlet in the outer wall, said valve when in open position permitting steam to enter through said inlet to initially contact the outer face of the inner wall and heat the same, and thereafter pass directly and freely through the opening in the base of the inner wall into contact with the hat crown, said outer wall being provided with a discharge opening in its base opposite the opening in the inner wall.

24. A device for use in steaming and pressing a hat which has been positioned in a flange, comprising a flexible strip capable of being coiled upon itself to fit within the hat and clamp the same to the flange, and a covering for said strip having a longitudinally extending pocket within which the strip is positioned, said covering being at least the length of the ordinary sweat band in order to completely seal the same.
